METHOD AND MEANS OF MAKING
FASTENERSFrederick M. Zenner, Wheatfield, N. Y., assignor
to Remington Rand Inc., Buffalo, N. Y.

Application October 14, 1936, Serial No. 105,551

20 Claims. (Cl. 1-2)

This invention relates to a method of making paper fastener bases and applying them to folders.

This application is in part a continuation of application Serial No. 27,221, filed June 18, 1935.

The present method invention provides for the manufacture of paper fasteners, particularly a type of fastener adapted for use on correspondence folders and comprehends a novel method of making the fastener bases and applying them to folders or other supporting sheets or backing members, in a simple, efficient and economical manner.

The method of the present invention comprehends the manufacture of fastener bases from a single strip of sheet metal, by forming the sheet metal in a progressive manner with outwardly projecting attaching prongs on the side edges arranged in pairs along each edge, the prongs on one edge corresponding with the prongs on the opposite edge, in a desired manner; the subsequent forming of suitable binder prong supporting means on the strip at spaced intervals arranged in a fixed relation with respect to the attaching prongs which are subsequently bent into a position to extend substantially perpendicular from the strip; and the final severing of the strip into sections each containing a set of prongs, one pair on each edge and a strap section in the central portion.

The invention further provides for the substantially simultaneous application of the severed base member to a folder or support sheet in one continuous operation including the clinching of the prongs to firmly attach the base member to the support sheet and the cutting of an opening in the sheet around the strap section so that the support sheet or backing member can then have a binding prong member inserted under the strap section on the inside of the backing member opposite to that on which the base member seats. In cases where it is desirable to emboss the folder to provide a recess for receiving the fastener base, the invention provides for the embossing operation on the folder at the time the fastener base is applied thereon.

The invention provides further for the accurate gauging of the operations above described on the strip in the progressive manner referred to through performing all of the operations before the base members are separated so as to accurately position the strip in each of a series of operating zones so that all of the parts on each base member will have a fixed relation

through this precision operation to provide base members that are of uniform construction.

The invention comprehends a novel method of making base members for paper fasteners with attaching prongs by forming portions of the prongs successively that are ultimately carried by each base member and completing the prongs in the next successive operation in forming a portion of the prongs on the next succeeding base member to be made from the strip.

This method further includes the use of a cut-out portion of the strip between a pair of the prongs made in one of the prong-forming operations, in cooperation with a gauge member, to secure the positioning of the strip for each operation thereon with precision, in order to overcome the variations occurring in the feed mechanism, that feeds the strip through the several zones where the successive operations are performed in making and applying the fastener bases to a folder or backing sheet.

The invention further comprehends the method of making a plurality of fastener bases in strip form and then simultaneous with the severing of each fastener base from the end of the strip in successive order it is immediately applied to a backing member or folder with the clinching of the attaching prongs on the base to this backing member or folder and the simultaneous cutting of an opening in the backing member to receive the means that support the paper binding structure on the backing sheet or folder.

Another feature of the invention resides in the mechanism for applying the fastener base to the folder, either with or without forming an embossment or recess in the folder to receive the base.

In the drawings:

Fig. 1 illustrates a fragment of a folder in perspective with a fastener applied thereto in accordance with the invention.

Fig. 2 is a cross section taken on line 2-2 of Fig. 1 showing the binder prong having the ends bent to extend in perpendicular relation to the folder.

Fig. 3 is a plan view of a length of sheet metal strip formed in accordance with the method of this invention, showing the progressive stages of formation of the strip from a plain sheet metal strip into connected fastener bases ready for severing from one end of the strip, portions of the forming dies and supporting structure for guiding and operating on the strip being shown diagrammatically in illustrating the features of the invention.

Fig. 4 is a bottom plan view of the strip as shown in Fig. 3.

Fig. 5 shows the strip as illustrated in Fig. 3 in side elevation with fragments of the dies and supporting structure shown diagrammatically or in fragmentary cross section in operative relation with the strip.

Figs. 6 and 7 are fragmentary cross sections through the severing punch taken at right angles to the plane of Fig. 5 showing diagrammatically progressive positions of the parts that sever a fastener base from the strip and illustrating how it is applied to a backing member or folder, how the prongs are clinched into position to hold the base member on the backing member or folder, and how the hole is cut in the backing member to accommodate the strap section, the line on which the second section is taken being indicated by the line 6—6 of Fig. 5.

Fig. 8 is a cross section showing fragments of some of the parts similar to the illustration at the right-hand end of Fig. 5, showing a modified form of construction of the punch device for severing a fastener from the strip, applying it to the folder, clinching the prongs on the folder, embossing the folder to provide a recess for receiving the fastener base, and cutting a hole in the folder to accommodate the strap section.

Fig. 9 is principally a cross section taken substantially on the line 8—9 of Fig. 8, but having the punch mounting structure shown in elevation with portions broken away to show some of the details of construction, the parts being in a position with respect to the cycle of operation of the device in which the punch has moved downwardly from the position shown in Fig. 8 to position the separated fastener base with the ends of the prongs ready to pierce the paper of the folder and the slideable clamping block moved downwardly from the position of Fig. 8 to firmly grip the folder between the block and the spring-supported ring member.

Figs. 10 and 11 are views similar to Fig. 9 having the parts shown in successively progressed position in the cycle of operation for applying a fastener base to a folder and for embossing the folder to provide a recess to receive the base.

Fig. 12 is a plan view showing the upper face of the spring-supported ring member and the prong clinching member, the tubular cutter 51 being omitted.

Fig. 13 is a vertical cross section taken on line 13—13 of Fig. 12, the lower portions of the ring member and clinching member being broken away, and a fragmentary portion of the lower end of the severing punch being shown in engaged relation with a fastener base and a fragmentary portion of a folder, the folder being embossed to receive the base; the illustration showing the end of the operation for applying the fastener base to the folder.

Fig. 14 shows fragmentary portions of the upper end of the spring-supported ring member and the clinching member used in connection with Figs. 8 and 9, in perspective and in disassembled relation.

Fig. 15 is a vertical cross section through a fastener base made according to this invention applied to a folder, only a fragmentary portion of the folder being illustrated, for the purpose of showing how the folder is embossed to receive and house the fastener base.

The completed fastener attached to a suitable backing or supporting member is illustrated in Fig. 1, the backing member being in the form of

a folder 1 provided with an opening 2 in one cover. As shown in Figs. 1 and 2 a fastener plate or base 3 is secured against the outer or back face of the flap of the folder or other backing and is formed on a pair of opposite edges with 5 pairs of attaching prongs 4 projected through folder 1 and bent down on the opposite face of the sheet to rigidly secure plate or base member 3 to the cover.

The central portion of plate or base 3 is formed with an offset strap section 5 in the central portion that projects through opening 2 in the cover of folder 1. As illustrated in Figs. 1 and 2 this strap section 5 provides a passage between the strap section and the adjacent face of base 3 for 15 the insertion of a binder prong 6 under the strap portion in the manner illustrated in Fig. 1. When the central portion is positioned under the strap portion as illustrated in Fig. 1 the ends may then be bent upwardly into the position 20 illustrated in Fig. 2 when they are ready to receive the papers that are to be bound together in the folder.

The fastener bases 3 are each formed from sheet metal by the novel method illustrated in 25 Figs. 3 to 7. A single plain sheet metal strip 7 having a width equal to the over-all dimension of base member 3 and prongs 4 is used. The method is preferably performed in a machine having parts specially arranged to carry out the 30 different operations at a series of spaced points or zones so as to successively form the strip in each zone in a progressive step-by-step manner to provide finished separate fastener bases.

In the first zone indicated generally at 8 in 35 Figs. 3 to 5 the opposite edges of strip 7 are recessed by removing portions of the side edges to provide in successive operations the attaching prongs 4.

The recesses may be formed preferably by a 40 cutting die having a shape generally indicated by the cross-hatched section indicated at 9 in Fig. 3. The dies 9 are formed to cut two recesses in opposite edges of the strip, one indicated at 10 which is a relatively narrow recess or slot so 45 as to provide two attaching prongs 4 in relative close relation but spaced from each other by the width of the slot 10. As will be seen from the following description the strip is severed between the two closely spaced tongues in the formation 50 of the fastener bases and from Fig. 3 it will be noted that in the formation of the slot 10 the die 9 also forms the adjacent sides of the two closely spaced tongues or prongs. In this formation of the closely spaced prongs the dies 9 will 55 form one-half of the prong indicated at 11, in that one side is formed by the part of the die providing the recess 10 and adjacent the outer edge of the strip a beveled portion 12 on the die provides one-half of the pointed end for the 60 attaching prong.

The die has a wide projection 13 to form the wide opening between the pair of prongs on each side of one base member and through the co-operation of the parts forming the recess 10 and 65 the wider recess 14 formed by the projections 13, the dies 9 form one complete attaching prong indicated at 15 in Fig. 3. At the opposite ends of the projections 13 on the dies from that forming the complete attaching prongs 15, each projection 13 is formed to cut one-half of the next attaching prong progressing to the left on the strip and is adapted to provide one-half of the 70 pointed end of the next attaching prong as indicated at 16.

The portion of the attaching prong so formed at the left-hand side of the projections 13 of dies 9 as shown in Fig. 3, will be advanced in the next operation on strip 7 in the direction of the arrow to the position of prongs numbered 11 in Fig. 3, so that dies 9 will form the other half of the prong in the manner in which it is shown forming prongs 11. In this way the dies 9 in one operation complete one prong on each side of strip 9 by forming a pair of recesses of different size in the strip and also completes two halves of two prongs at opposite sides of the completed prong 15 in the manner clearly shown in Fig. 3. In the next operation where the strip is moved one step in its progressive feeding through the series of zones, the strip is positioned so the other half of the second prong on one base member is completed, to complete the pair of spaced prongs on said base member, and at the same time partially forming one and one-half prongs on the next succeeding base member.

25 In the operation of dies 9, it will be understood that complementary die blocks are positioned under strip 7 as shown in Figs. 3 to 5 for coaction therewith, the die blocks not being illustrated. Fig. 5 illustrates the position of dies 9 relative to strip 7 in side elevation at rest, in inoperative position, at their upper limit of movement ready for the next cycle of operation, and also shows the relation between the dies 9 and the other members that are employed in conjunction therewith for the formation of the strip in a manner 30 to be described.

35 A suitable conventional feeding mechanism for feeding the strip 7 in step-by-step progressive motion in the direction of the arrows shown in Figs. 3 and 4, is provided on the machine mount-
40 ing the parts diagrammatically illustrated in the drawings, any well known feeding mechanism being used, which is not disclosed, because it does not form part of the invention and is not necessary to a clear understanding of the method of manufacturing the fastener bases.

45 The strip 7 progresses to the second zone after the formation of attaching prongs 4 in the manner above described, where a gauging member 17 having a tapered end portion 18 is used to accurately gauge the position of the strip in all of the zones of operation. This gauge member 50 17 has a width equal to the distance between the adjacent edges of a pair of the prongs on one base member so that the side edges of gauge member 17 will engage the adjacent side edges of the attaching prongs on each successive portion or section of strip 7 that forms a base member 4. When gauge member 17 descends from the position shown in Fig. 5 to a lowered position through or past strip 7 the side edges above the tapered end 18 will engage between prongs 60 4 in the manner described above, and as shown in Fig. 3, and through the accurate positioning of the gauging member 17 with reference to the other forming elements, such as dies 9, strip 7 is moved back or forth longitudinally to accurately position the strip for each successive operation thereon by the dies 9 and the other operations 65 hereafter described.

In this way all of the attaching prongs 4 will be formed of a uniform size and uniformly spaced apart by the dies 9 and all of the other parts of the strip will be formed with accuracy and precision so that all of the parts on each successive section which forms a base member when separated from the strip will be uniformly arranged in relation to each other so that all of

the base members will be of duplicate construction. The operative relation of gauge member 17 and dies 8 is shown in Fig. 5, these parts being mounted on a supporting and operating plate or block not shown, which moves these members up and down in their operations upon the strip simultaneously.

In the third zone of operation a punching die 19 fixed in the relation shown in Fig. 5 to the dies 8 and gauging member 17, is arranged to move simultaneously therewith and to operate on the center of the strip in the manner illustrated in Figs. 3 to 5, to form strap portions 5. It will be noted from Figs. 3 and 5 that as die 19 descends onto the top of strip 7, it engages in the central portion and is so positioned that it is located centrally between the side edges of the strip and also between a pair of spaced prongs 4 that are provided on one of the successive sections of strip 7 subsequently separated to form a fastener base. When die 19 descends into engagement with the strip for the formation of strap sections 5 it will be noted that it depresses the strap sections downwardly from strip 7.

Strip 7 is slit at a pair of spaced points indicated at 20 extending transversely of strip 7 so that a portion of the strip is separated from adjacent portions in order that this portion may be depressed and offset from strip 7 to form offset strap section 5. 300

As shown in Fig. 5 a die block 21 is provided on the supporting structure indicated at 22 of the machine for forming strip 7. This die block is formed with an opening 23 the size of the die 19, so as to slidably and telescopically receive the same together with the portions of strip 7 forming strap sections 5. Below the recess or opening 23 there is provided an enlarged opening 24 in the die block to receive a plunger 25 slidably mounted in block 21 and urged upwardly by spring 26. The plunger 25 is provided with a projection 27 slidably mounted in opening 23 and formed to be complementary to die 19 so as to cooperate with the die in the formation of strap sections 5 in the offset relation illustrated. It will be noted that this strap section is offset to an extent sufficient to provide a passage on the side of the base 3 from which the strap section projects, so that prongs 6 can be slidably inserted under the strap section and over the face of the base. After a strap section 5 is offset by die 19 in the third zone, plunger 25 pushes the strap section out of die block 21 and in the next movement of strip 7 in the direction of the arrow in Figs. 3 and 4 the bottom face of strap section 5 will ride on top of die block 21 a short distance until it reaches the slot indicated in dotted lines at 28 in Figs. 3 and 5, when it will drop into this slot so that the strip will then ride on the face of the die block as shown in Fig. 5.

The next zone of operation secures the bending of attaching prongs 4 into laterally extending relation from strip 7. After strip 7 leaves the zone for the formation of strap sections 5 it moves on to a die block 29 adjacent to die block 21, block 29 being formed with a portion of the slot 28. The die block 29 is formed with recesses 30, Fig. 3, adjacent opposite edges of strip 7. Under the central portion of the strip the die block is constructed to receive a guide strip 31 having a width equal to the distance between the inner ends of the recesses in opposite sides of the strip so that the prongs may be bent laterally against the opposite side edges thereof, and so that the strip with the prongs in his laterally 75

extending position may be slidably moved and guided along this strip 7.

A die member 32 is provided at the lower end with a pair of spaced forming legs 33 so arranged that when the die 32 is moved downwardly from the position shown in Fig. 5 into engagement with strip 7 and in cooperation with die block 29 and guide 31, the legs 33 will engage four of the attaching prongs on each edge of strip 7 and bend them into laterally extending position. This operation is such that while die 32 engages four of the prongs, it bends them laterally in groups of two on each side and in the next operation the group of two previously bent laterally is again engaged in order to insure the complete bending of the prongs into perpendicular relation to strip 7 in a uniform manner.

It will be noted from Fig. 3 that die 32 operates on the prongs of two successive sections of strip 7 that are subsequently detached to form two bases 3. Die 32 is mounted on the same operating and supporting member that carries dies 8 and 18 and gauging member 17, and the relation between these parts is clearly illustrated in Fig. 5, all of them moving simultaneously in the operation of the machine to perform their respective operations as described hereinabove, simultaneously, on different portions of strip 7 in the separated zones of operation described.

It will be clearly understood that the strip is fed in a step-by-step motion a distance equal to the width of one fastener base 3 in each successive movement of the strip in the direction of the arrows as shown in Figs. 3 and 4, and as a result attaching prongs 4, and strap sections 5 are progressively formed on the strip into their completed relation with the attaching prongs depending from strip 7 in perpendicular relation as illustrated.

Following this operation the feeding of the strip as shown in Figs. 3 to 5 will move the end which is formed with the completed and connected fastener bases ready for separation to the right along guide 31 into the severing and attaching mechanism indicated at 34 and illustrated in Figs. 5, 6 and 7. A stationary supporting and guide structure 35 is formed with a passage 36 to receive the end of strip 7 as it leaves guide 31.

A plate 37 is attached to supporting and guide structure 35 as shown in Fig. 5 and has a passage 38 registering with passage 36 also formed to receive and support one end of guide 31 which is suitably secured therein by the screw 39. In the illustration in Fig. 5 it will be understood that passages 36 and 38 are formed with a central groove portion to slidably receive the under face of the central portion of strip 7 formed with strap sections 5 while at the side edges of the strip they are formed with depending slots 60 to receive and slidably accommodate the depending prongs 4 on the side edges of the strip. In Fig. 5 the section through supporting and guide structure 35 is taken on a line extending along the central groove portion while strip 7 is shown in side elevation for the purpose of indicating the general arrangement of the parts to secure the guiding and other operations on the strip.

Supporting and guide structure 35 is formed at the right-hand end as shown in Fig. 5 with a vertical square slot 40, closed by plate 41 secured thereto to form a square vertical guideway for the severing punch 42. The size and shape of the severing punch is indicated by the cross hatch section in Fig. 3 and it will be seen that it has a size suitably adapted to the severing of

one base member at a time in successive operation from the end of strip 7. Passage 36 communicates with guideway 40 so that as strip 7 is fed to the right as shown in Figs. 3 to 5 the end will be projected into guideway 40 from passage 36 so that one base member will project into guideway 40 ready for severing from the end of the strip in the next operation of severing punch 42.

This severing punch 42 is mounted on the same supporting structure that supports dies 8, 18 and 32 and in the position of these parts as illustrated in Fig. 5 this severing punch normally has the lower end positioned as indicated in dotted lines in Fig. 5 by the numeral 43. The full line 15 position of the severing punch 42 in Fig. 5 shows its position after it has moved downwardly in the direction of the arrow part of its stroke, the punch having severed one fastener base 3 from strip 7 with the severed base 3 moved 20 downwardly in guideway 40 part of its movement so that it can be applied to a folder in the subsequent downward movement in a manner that will now be described.

After each fastener base is severed from strip 25 7 it may be discharged from the lower end of passage 40 and collected in a suitable container if it is not desired to immediately apply the fastener bases to folders or backing members. However, as these fastener bases are used for 30 the most part on backing sheets and folders, it is desirable to immediately apply each base to the backing sheet or folder in which it is to be used. Suitable means is provided for this purpose in which the supporting base 22 is formed with a 35 cylindrical bore 44 in axial alignment with guideway 40. A guide and supporting table 45 is mounted immediately above base 22 and formed with a cylindrical opening in axial alignment 40 with bore 44.

A spring supported ring member 46 is normally projected upwardly through bore 44 so that the annular flange on the lower end engages shoulder 47 which positions the upper end in spaced relation just below the lower end of guide and supporting structure 35 in axial alignment with guideway 40. Ring 46 is provided with a square central opening 48 of a size approximately that of a fastener base 3. A clinching member 49 is mounted inside ring 46, slidably receives said ring and is provided with a squared end 50 slidably engaging in squared opening 48. Clinching member 49 is operable in bending prongs 4 inwardly toward each other in the manner illustrated in Figs. 6 and 7, to clinch them on a folder or backing sheet. The inside of clinching member 49 is hollow and a tubular cutter 51 is mounted in said member for cutting the hole 2 in the folder or backing sheet.

The manner in which these parts cooperate will be best understood by a description of the operation of the several parts in reference to Figs. 5, 6 and 7. Ring 46, clinching member 49 and cutter 51 are in their normal inoperative 65 positions in Fig. 5 ready to start a cycle of operation. Clinching member 49 and cutter 51 are mounted in fixed, but adjustable, relation on support 22 in any convenient manner (not shown) well known in the art, below the mounting for 70 ring 46. As above stated, severing punch 42, as shown in Fig. 5, has moved downwardly from the dotted line position 43 to the full line position and has severed one fastener base from strip 7. The further movement of severing punch 42 75

pushes the severed fastener base downwardly in passage 40.

Just prior to the starting of this operation a folder or backing sheet is inserted into the machine by placing it on table 45 and sliding it between ring 46 and the lower end of supporting structure 38, as shown. Suitable positioning guides are mounted on table 45 to position each folder or backing sheet so the fastener will be applied thereto at the desired point, these guides being well known in the art and not being shown in the drawings. With the folder positioned as illustrated in Fig. 5 and indicated by numeral 1, the severing punch 42 upon descending downwardly from the position shown in Fig. 5 will force the separated fastener base downwardly toward the folder or backing sheet 1 so as to extend the beveled ends of prongs 4 through the folder 1 into engagement with ring 46 and clinching member 49 to the positions shown in Figs. 6 and 7.

As shown in Fig. 6, ring 46 is formed at opposite ends of opening 48 with beveled portions 53 with which prongs 4 engage immediately upon piercing the paper or other material of folder 1 so that the bending of attaching prongs 4 toward each other is started as the downward movement of punch 42 continues after the ends of the prongs engage beveled faces 53. These prongs are folded inwardly in the further downward movement of punch 42 until the ends engage clinching member 49 as shown in Fig. 6. The punch then continues its downward movement to complete the clinching of the base on the folder to bring the parts into the position shown in Fig. 7.

In this further downward movement of punch 42, ring 46 is depressed against the tension of the spring and the fastener base is moved downward toward the upper end of clinching member 49 and cutter 51. This folds the prongs 4 into engagement with the folder as shown in Fig. 7. As the clinching of the prongs is completed the folder is forced down onto cutter 51 so that a piece is cut out of the folder to provide hole 2. Fig. 7 shows the completion of this operation with punch 42 at its lower limit of movement. In this position the fastener base is just about touching the upper end of cutter 51 so that a clean cut is made in forming opening 2 while strap section 5 acts to eject the disc cut out by the cutter. Prongs 4 are tightly compressed in folded position on the folder so that the base is rigidly attached thereto. The punch then moves upwardly and ring 46 follows until its flange engages shoulder 47. Then the punch continues its upward movement to the starting position 43 and the backing or folder with the attached fastener base is removed so the next folder may be inserted to repeat the operation successively. Cutter 51 has a conventional mounting relative to clinching member 49 so that it may be adjusted into proper relation therewith, this mounting not being shown. The completed folder is shown in Fig. 1, a prong 6 having been inserted under strap section 5.

From the above description it will thus be understood that a series of folders may have fastener bases applied thereto in successive relation by feeding them successively under punch 42 in the manner above described and that a strip of material 7 is progressively formed with attaching prongs 4 and strap members 5 in spaced relation with the prongs bent laterally, after which sections to form separate fastener bases are sev-

ered from the end of the strip in successive order, and the separate fastener bases successively applied to backings or folders. It will also be noted that gauge member 17 positions strip 7 for all of the operations including the severing operation by severing punch 42, so as to form fastener bases that have the strap sections in fixed relation to the edges thereof and in which all of the bases are of uniform construction and dimension. Gauge member 17 cooperates particularly with dies 9 in the formation of prongs 4 on opposite edges of the strip so that in one operation dies 9 form portions of the prongs on one base member and then in the next successive operation completes these prongs on the one base member while portions of the prongs on the next base member are formed, this method providing a novel way for making beveled attaching prongs with sharp ends that are adapted to pierce the paper of the material to which the fastener base is to be applied.

It will undoubtedly be clear to one skilled in the art that the completed fasteners may be left in strip form if desired so that sections of the strip 7 may be cut off from time to time containing a number of fastener bases. These strip sections containing a number of fastener bases could subsequently be inserted into a base applying mechanism similar to that disclosed in Figs. 5, 6 and 7, or in the remaining figures of the drawings, for the purpose of severing the individual fastener bases from one another and applying them in the proper manner on suitable folders.

The drawings illustrate a modified form of the invention in Figs. 8 to 15 inclusive. The purpose of this modified form of construction is to add a further step in the method of manufacturing the fastener bases and applying them to folders that will provide for the offsetting or embossing of the material forming folder 1 to form a recess for receiving the fastener base. When the fastener base is applied in the recess, the outer face will lie flush with the back face of the folder and will prevent the base from catching on adjacent files while being removed and inserted in a file drawer or cabinet.

Fig. 8, which is a section similar to the right-hand portion of Fig. 5 showing a fastener severing and attaching mechanism, shows 50 a fragment of supporting base 22 constructed in the same manner as shown in the previous figures with guide and supporting table 45 above base 22 formed with an aperture aligned with bore 44. Shoulder 47 is the same structure 55 shown in Fig. 5.

Guide 31 is attached by screw 39 to plate 37 as hereinabove described. Plate 37 is provided with a passage 38 for fastener strip 7. The supporting and guide structure aside from plate 37 60 is constructed in a slightly different manner from the disclosure of Figs. 5 to 7. This supporting and guide structure is indicated by the numeral 54 and is provided with guideway 55 from which extend grooves 56 at opposite sides.

Guideway 55 slidably receives slidable clamping block 57 retained in position by plates 58 detachably mounted on supporting and guide structure 54 by screws 59. The lower ends of slots 56 are closed. These slots form housings 70 for two springs 60, one positioned at each side of slide block 57 having the lower ends seated at the bottom of the slot on guide and supporting structure 54, while the upper ends engage opposite ends of cross pins 61 slidable in grooves 75

58 and mounted in the upper end of slide block 57. Springs 60 normally hold slide block 57 at its upper limit of movement.

10 A vertical groove in slide block 57, of square cross section, slidably receives, severing punch 62. A retaining plate 63 secured to slide block 57 by screw 64 mounts severing punch 62 in the groove of slide block 57 for sliding movement. The lower end of plate 63 which lies between 15 plates 58 is provided with shoulders 65 extending underneath the lower edges of plates 58 and may be used to form a positive stop to limit the upward motion of slide block 57 under the action of springs 60 to prevent disengagement of the 20 upper end of the slide block from supporting and guide structure 54.

25 The upper end of severing punch 62 is formed with a reduced screw-threaded extension 66. A nut 67 is threaded on extension 66 adjacent the 30 upper end of the squared portion of punch 62 and has its periphery overhanging the edges of the squared portion of punch 62 so as to engage the upper end of slide block 57 as hereinafter described. The upper end of reduced threaded section 66 engages the lower end of threaded sleeve 35 68 having the threads thereon threadedly engaging in the supporting and operating plate 69. This supporting and operating plate 69 of which only a portion is shown in the drawings, is the 40 plate that carries all of the forming dies for the metal strip 7 in forming the fastener bases.

45 A bolt 70 is extended through sleeve 68 having its head seating on the upper end of the sleeve and its lower end threadedly engaged in a 50 threaded socket in the upper end of severing punch 62. This firmly secures severing punch 62 to the supporting and operating plate 69 in a manner that it may be adjusted to properly 55 position the relation of the lower end with respect to the rest of the parts of the fastener 60 severing and attaching mechanism so that it will be in proper position to effectively apply the fastener base to a folder. Adjustments of sleeve 68 may be made from time to time to compensate 65 for wear or sharpening or to control the extent of the embossment of the folder and the compactness of the clinching operation on the fastener prongs.

70 A pair of actuating pins 71 are slidably mounted 50 in supporting and operating plate 69, one on each side of sleeve 68 as clearly shown in Fig. 9, for example. The upper ends of pins 71 have heads that are adapted to engage on the upper surface of plate 69. Coil springs 72 are housed 55 in casings 73 mounted on plate 69 under compression to normally maintain the heads of pins 71 in engagement with the upper face of plate 69. The lower ends of pins 71 are aligned with slide block 57 adjacent the opposite sides thereof so 60 that when operating plate 69 descends in its cycle of movement, the lower ends of pins 71 will engage the upper end of slide block 57 and through the action of springs 72 which are designed to overcome the tension of springs 60, slide block 57 65 will be moved downwardly in its guideway in the supporting and guide structure 54 to produce the operation hereinafter described.

75 Spring supporting ring member 74 for the most part, is identical in construction with ring member 48. The difference is in the formation of the parts that receive and operate on the fastener base in clinching the tongues and in the embossment of the folder. Spring supported ring member 74, as shown most clearly in Figs. 12 and 14, 80 is formed with a square opening 75 having an

enlarged portion 76 at the upper end of opening 75 of a size and shape to receive the offset or embossed portion 76' formed in folder 1 as illustrated in cross section in Fig. 15, so as to cooperate with severing punch 62 and the fastener base in offsetting or embossing the folder in this manner. Inclined portions 77 in ring member 74 engage the ends of the prongs on a fastener base just after they have pierced the paper of the folder and turn them inwardly toward each other for the initial clinching operation.

85 A clinching member 78 similar to clinching member 49 is mounted inside of spring supported ring member 74 as shown in the drawings. The upper end of clinching member 78 is provided with a squared portion 79 as most clearly illustrated in Figs. 12, 13 and 14 that slidably engages in squared opening 75 of ring member 74. The upper end of the squared portion 79 is provided with central projections 80 in the central portion of each side for the purpose of cooperating with ring member 74 and punch 62 in embossing the folder and firmly attaching a fastener base thereto. The corner portions are at a lower level than the upper ends of projections 80 in order to 90 accommodate the thickness of the metal forming the fastener prongs so that each of the prongs will have the ends engaged on the upper end of squared portion 79 between projections 80 when they will be forced against the under base of the 95 folder into the finally clinched position as illustrated in Figs. 11 and 13.

100 A tubular cutter 81 identical with cutter 51 is located inside of clinching member 78 and adjustable with respect thereto so as to cut the opening 2 in the folder. Fig. 11 shows the tubular cutter and clinching member mounted on a supporting plate 82 detachably secured in a suitable manner to supporting base 22.

105 The dotted line 43 in Fig. 5 illustrates the upper limit of movement of severing punch 62. Severing punch 62 as shown in Figs. 8 to 11 has this upper limit of movement at approximately the same relative position to the supporting and guide structure.

110 Fig. 8 shows severing punch 62 moved downwardly from this upper limit of movement into a position where it has severed a fastener base from the end of strip 7 and moved the same downwardly a partial distance toward the lower end of the supporting and guide structure where it is applied to a folder. In the further operation of the structure disclosed in Figs. 8 to 11 inclusive, to complete one cycle of operation for applying a fastener to a folder and embossing the folder, the supporting and operating plate 69 moves downwardly so as to move severing punch 62 downwardly from the position of Fig. 8. The next position in the progressive movement of punch 62 downwardly is illustrated in Fig. 9, at 115 which point the punch 62 has moved the separated fastener base into a position where the ends of the prongs are just about to pierce the paper of the folder. The folder 1 has been inserted between the lower end of the supporting and guide structure and the upper end of ring member 74, previous to this downward movement of punch 62, and positioned by suitable guides, not shown, carried by guide and supporting table 45.

120 As punch 62 moves downwardly from the position of Fig. 8 to that shown in Fig. 9 actuating pins 71 are brought down into engagement with the upper end of slide block 57 so that when the punch is moved to the position of Fig. 9, slide block 57 will have been moved downwardly a 75

slight extent, sufficient to have the lower ends engage the upper face of folder 1 and move it against the upper end of spring supported ring member 74, so as to firmly grip the paper between these two members.

Opposite sides of the lower end of slide member 57 are beveled slightly as shown in Figs. 9, 10 and 11, so the central portion immediately above the upper end of ring member 74 forms the part that engages and clamps the folder against ring member 74 entirely around the portion that receives the fastener base.

In the further downward movement of supporting and operating plate 69 severing punch 62 is moved downwardly to force the ends of the prongs on the fastener base through the paper of folder 1 into engagement with inclined surfaces 77 of spring supported ring member 74.

The next step of movement progressing from that shown in Fig. 9 as above described, is illustrated in Fig. 10, showing the prongs partially turned in toward each other through engagement with the inclined faces 77. As severing punch 62 moves from the position shown in Fig. 9 to that shown in Fig. 10, it will also be seen that the fastener base has been moved into engagement with folder 1 and the portion immediately adjacent the fastener base has been offset into the enlarged embossing portion 76 (Fig. 14) of ring member 74 to emboss the folder. The strap section on the fastener base is shown as engaged with the paper of the folder immediately thereto which it is pushing downwardly toward tubular cutter 81. Ring member 74 is shown as having its flange engaged with shoulder 47. It will also be noted in Fig. 10 that nut 67 has moved downwardly with severing punch 62 until it has engaged the upper end of slide block 57. In this position it will be noted that the adjustment of nut 67 has been made so that the lower end of punch 62 is flush with the lower face of slide block 57. This holds the fastener base in such a position that it forces the paper into enlarged portion 76 of ring member 74 in obtaining the embossing operation on the folder at the same time as the fastener base is seated in the depression formed by the embossment.

By slide block 57 engaging the paper around enlarged portion 76 between its lower end and the upper end of ring member 74 the paper of the folder is firmly held in position so that it may not be buckled in any way in forming the embossment in an efficient manner through forcing the paper into enlarged portion 76.

In the further downward movement of punch 62, slide block 57 is moved downwardly due to the operation of nut 67 engaging its upper end, and ring member 74 is moved downwardly until the position illustrated in Fig. 11 is reached.

During this further downward movement which completes the downward stroke of the cycle of operation of punch 62, the downward movement of ring member 74 provides for the clinching of the fastener prong against the under face of the folder through the operation of clinching member 78. As the ring member moves downwardly the ends of the prongs engage the end of squared portion 79 at the corners and between projections 80, and flatten out these prongs on the fastener base to tightly clinch them against the paper of the folder. At the same time, tubular cutter 81 cuts a circular aperture in the paper to form opening 2 as shown in Fig. 1, so the strap portion of the fastener base can project through the opening to the inside face of the folder. The

strap section serves to eject the disc cut out of the folder to form opening 2 toward the bottom open end of tubular cutter 81. The disc cut from the folder is shown in Fig. 11 in partially ejected position. Projections 80 on clinching member 78 operate to push the paper over the fastener base up against the base in the final clinching operation of the prongs so that the paper will not be torn and also to cooperate in securing the embossing of the paper to receive the fastener base in a final pressing operation on the paper so that the embossment is well formed and the paper will not bulge around the strap member after the opening 2 is cut in the paper.

From the position shown in Fig. 11 operating plate 69 moves upwardly and carries with it punch 62. Slide block 57 is raised up initially by the spring operating ring 74 and then through the operation of springs 60 as soon as operating plate 69 is moved upwardly to a point where the heads on pins 71 engage its upper face and begin to move upwardly with it. As soon as slide block 57 is moved upwardly to free the folder from being clamped between it and ring 74, the folder may be removed and another one inserted for a repetition of the operation to apply a fastener base.

It will be noted from Figs. 11 and 13 and also Fig. 15 how the embossment is arranged in the folder with respect to the marginal edges of the fastener base and the prongs thereon. Fig. 11 shows a section taken through the fastener base in the central portion extending through the strap section and through the two sides provided with the fastener prongs. Fig. 13 shows a section taken in a plane parallel to that shown in Fig. 11 but over to one side of the fastener base in order to illustrate the cross section through the fastener base and folder where it is formed with the prongs. The embossment as illustrated in Fig. 13 extends outside of the bent portion of the prong. Fig. 13 also illustrates how the clinching member receives and clinches the prongs against the opposite face of the folder from the remaining portion of the fastener base and how the prongs are received at the corners on the ends of squared portion 79 of the clinching member adjacent to projections 80. Fig. 13 also illustrates one of the projections 80 and the manner in which it cooperates with punch 62 in applying the fastener base to the folder and offsetting the folder.

The fragment of the folder illustrated in Fig. 15 shows the fastener base applied in the embossed portion 76 and illustrates the completed operation of applying the fastener base to the folder, a prong member being shown applied to the strap section of the fastener base and having its ends bent into parallel relation ready to receive papers for filing thereon.

Severing punch 62 occasionally requires sharpening of the lower end in order to operate efficiently in cutting off the fastener bases from strip 1. This, of course, necessitates the grinding off of the end of punch 62 and when it is replaced in slide block 57 adjustment of its relative position to the slide block and operating plate is required in order to secure the operation described above. Threaded sleeve 68 is provided for this purpose and may be adjusted in supporting and operating plate 69 in order to compensate for this sharpening of the end of punch 62. Nut 67 will also be adjusted in order that the lower end of punch 62 and the lower end of slide block 75

51 will operate in the proper relation to one another.

If desired, the severing and attaching mechanism for severing fastener bases and attaching them to folders may be entirely omitted and the fastener bases formed in strip 7 allowed to remain in strip form. They may be made in predetermined lengths or a severing mechanism may be made to operate independent of the remaining portions of the forming mechanism for strip 7 so that predetermined lengths of the strip 7 formed into connected fastener bases may be severed. The severing and attaching mechanism may then be mounted in a separate operating mechanism of conventional form to secure the cycle of motion of punch 62 and its associated parts as described above, for severing fastener bases from a strip of connected bases and applying these bases in the manner described, to a folder.

This applies either to the form of the invention shown in Figs. 5 to 7 or in the modified form of construction shown in Figs. 8 to 15 where the folder is embossed in connection with the application of a fastener base.

The invention claimed is:

1. A method of making paper fastener bases consisting in intermittently feeding a sheet metal strip through a series of treatment zones, removing portions from the opposite edges of said strip in one zone to form an outwardly extending attaching prong on each side of said strip and portions of two other attaching prongs on each side 35 of said strip on opposite sides of the first mentioned prong, one of said prong portions being complementary to the other whereby the next operation on an adjacent portion of said strip will complete said other prongs, gauging the position of said strip in another of said zones to obtain uniform cutting of said strip in forming said prongs in the first-mentioned zone, offsetting the central portion of said strip to form a strap member in another zone, bending said prongs laterally in another zone, subsequently severing sections 45 from said strip having a pair of the prongs on each side formed in the first mentioned zone adjacent opposite ends thereof, and substantially simultaneously applying said separated section to a backing sheet to project said prongs through the sheet, bending the prongs over the other side of the sheet to clamp the separated strip section thereon and removing a portion of the sheet between said prongs to provide an aperture for said strap portion.

55 2. A method of making paper fastener bases, consisting in intermittently feeding a sheet metal strip through a series of treatment zones arranged at predetermined spaced intervals along the strip, removing successive portions of the side edges of said strip in one zone in successive operations in said zone to form attaching prongs, punching said strip successively in another zone to form pairs of slits in said strip in spaced parallel relation and simultaneously offsetting the portion between the slits to form a strap section in each operation in said zone, subsequently severing a section from said strip in another zone successively in each operation to form separate 60 fastener bases each having prongs on opposite sides and a strap section in the central portion, and positioning said strip accurately for each operation in each of said zones to uniformly space said attaching prongs and strap sections on each 75 of said bases when severed, by engaging a position-

ing member in successive recesses in the side of said strip between prongs formed in the first-mentioned operation.

3. A method of making paper fastener bases, consisting in intermittently feeding a sheet metal strip through a series of treatment zones arranged at predetermined spaced intervals along the strip, removing successive portions from the edges of said strip in one zone to form portions of a set of attaching prongs on successive sections of the strip, the next operation on the next succeeding section of the strip in said zone completing the prongs on the preceding section, positioning said strip accurately in each zone by engaging a positioning member successively between the prongs on each strip section in another zone to obtain a fixed relation between all of the prongs on said strip, forming a binder prong mounting on successive sections of said strip in another zone, and finally severing each section 20 from said strip successively to form separate fastener bases having attaching prongs and a mounting for a binder prong.

4. A method of making paper fastener bases, consisting in intermittently feeding a sheet metal strip linearly through a series of treatment zones, removing portions from the opposite edges of parts of two successive sections of said strip in each operation in one zone to form an outwardly extending attaching prong on each side of said strip in one section and portions of two other attaching prongs on each side of both sections of said strip and at opposite sides of the first-mentioned prong, one of said prong portions being complementary to the other, the next operation 35 in said zone on the next succeeding sections of said strip successively completing a second prong on each side of the section of said strip having the completed prongs, forming each section of said strip successively in another zone with 40 binder prong holding means, and finally severing each section from said strip successively in another zone to provide separate bases having a pair of attaching prongs on each side and a binder prong holding means.

45 5. A method of making paper fastener bases, consisting in intermittently feeding a sheet metal strip linearly through a series of treatment zones, removing successive portions from an edge of said strip in one zone to form recesses defining 50 portions of a set of attaching prongs on successive sections of said strip, the next operation on a succeeding section of said strip in said zone completing the prongs on the preceding section, gauging the position of said strip in another zone by means of the recesses formed in the first-mentioned zone to accurately position the strip for the operations performed in all of said zones, forming each section successively in another zone with binder prong supporting means, 60 and finally severing each section successively from said strip in another zone to provide separate fastener bases having attaching prongs and binder prong supporting means thereon.

6. A method of making paper fastener bases 65 consisting in progressively and successively forming a sheet metal strip by cutting out portions along the edges to form attaching prongs on opposite edges, then offsetting successive sections of said strip to provide a series of strap 70 sections, then bending said prongs into laterally extending relation successively in groups, then severing each formed section of said strip at the end to successively form separate fastener bases, each having one strap section and a plurality of 75

- attaching prongs, then upon completion of the severing directing the prongs on each separated base through a separate backing sheet fed thereto and simultaneously folding said attaching prongs against the opposite face of the backing sheet and simultaneously cutting a hole in said backing sheet to receive said strap section and provide for insertion of a binder prong under said strap section.
10. A method of making paper fasteners, consisting in intermittently notching opposite sides of successive portions of a sheet metal strip to form attaching tongues, then offsetting central strip portions of each successive portion to provide a strap portion at one side of said strip uniformly arranged with pairs of said attaching tongues, and bending said tongues to extend laterally from the same side of said strip as said strap portion to provide a strip of completed attached fastener bases.
11. A method of making paper fastener bases consisting in progressively and successively forming a sheet metal strip by cutting out portions along the edges to form attaching prongs on opposite edges, then offsetting successive sections of said strip to provide a series of strap sections, then bending said prongs into laterally extending relation successively in groups, subsequently severing each formed section of said strip at the end to successively form separate fastener bases, each having one strap section and a plurality of attaching prongs, then upon completion of the severing directing the prongs on each separated base through a separate backing sheet fed thereto, substantially simultaneously folding said attaching prongs against the opposite face of the backing sheet and embossing said backing sheet to receive said fastener base, and simultaneously cutting a hole in said backing sheet to receive said strap section and provide for insertion of a binder prong under said strap section.
12. A method of making folders with attached fastener bases consisting in severing a fastener base having attaching prongs and a strap section formed therein from a strip having a plurality of said bases in attached relation, feeding the separated fastener base to a backing sheet to project the prongs on the fastener base through said backing sheet, embossing the portion of said folder in the zone of said fastener base to provide a recess for receiving said fastener base, substantially simultaneously clinching the prongs on the opposite face of said backing sheet to attach said fastener base in the embossed portion of said backing sheet, and simultaneously cutting a hole in said backing sheet to receive said strap sections and provide for insertion of a binder prong under said strap section.
13. A method of applying paper fastener bases to a folder consisting in successively severing a fastener base having laterally extending prongs and a strap section from a strip formed with a plurality of connected fastener bases, feeding said separated fastener base to a backing sheet and projecting the prongs of said fastener base through said backing sheet, simultaneously folding said attaching prongs against the opposite face of said backing sheet and cutting a hole in said backing sheet to receive said strap section and provide for insertion of a binder prong under said strap section.
14. A device for attaching fastener bases to backing sheets wherein the fastener bases are made in strip form and provided with laterally extending attaching prongs, comprising a spring supported ring member formed with portions to receive portions of a fastener base with its prongs, a stationary clinching member mounted in said ring member, a tubular cutter mounted in said clinching member and adjustable relative thereto, and a severing punch for severing a fastener base from said strip, feeding said separated base to project the prongs through a backing sheet supported on said ring member, and for continuing the movement of said fastener base, and backing sheet with said ring member toward said clinching member and tubular cutter for clinching said prongs against said backing sheet and cutting an aperture through said backing sheet over said fastener base.
15. A device for attaching fastener bases to

backing sheets and embossing said sheets where-
in the fastener bases are in strip form and have
laterally projecting attaching prongs, comprising
a spring-supported ring member, a stationary
5 clinching member in said ring member adjustable
relative thereto, a stationary cutter in said clinching
member adjustable relative thereto, said ring
member and clinching member having parts
formed thereon for cooperation in embossing a
10 backing sheet and clinching the prongs on a fastener
base, and a reciprocable severing punch
for severing a fastener base from said strip, feed-
ing it toward said members and cutter to project
said prongs through a backing sheet into engage-
15 ment with the cooperating parts of said ring and
clinching members, and finally move said fastener
base, backing sheet and ring member toward said
clinching member and cutter for firmly clinching
said prongs on said folder, embossing said
20 folder to form a recess receiving said base and
cutting an aperture in said folder over said fastener
base.

16. A device for attaching fastener bases to
backing sheets and embossing said sheets where-
25 in the fastener bases are in strip form and have
laterally projecting attaching prongs, comprising
a spring-supported ring member, a slide block
mounted for sliding movement toward and away
from said ring member, a stationary clinching
30 member in said ring member adjustable relative
thereto, a stationary tubular cutter in said
clinching member adjustable relative thereto,
and a reciprocating severing punch slidable
in said slide block and having adjustable means
35 for actuating said slide block in the move-
ment thereof, whereby said punch will sever a
fastener base from said strip, feed it to project
the prongs through the backing sheet, operate
said slide block to engage and clamp said backing
40 sheet between it and said ring member prior to
said fastener base prongs piercing said backing
sheet, move said slide block and fastener base for
embossing said folder by engagement in cooper-
ating portions of said ring and clinching mem-
bers, and move said ring member therewith to
45 clinch said prongs against said embossed backing
sheet and cut an aperture in said sheet over the
central portion of said fastener base.

17. A method of making paper fastener bases,
50 consisting in intermittently feeding a sheet metal
strip lineally through a series of treatment zones,
removing portions from the opposite edges of
parts of two successive sections of said strip in
each operation in one zone to form an outwardly
55 extending attaching prong on each side of said

strip in one section and portions of two other at-
taching prongs on each side of both sections of
said strip and at opposite sides of the first-men-
tioned prong, one of said prong sections being
complemental to the other, the next operation in
said zone on the next succeeding sections of said
strip successively completing a second prong on
each side of the section of said strip having the
completed prong, and forming each section of
said strip successively in another zone with bind-
er prong holding means, to provide a strip of
completed attached fastener bases. 10

18. A method of making folders with attached
fastener bases consisting in feeding a fastener
base having attaching prongs and binder prong
15 attaching means thereon to a backing sheet to
project the attaching prongs on the fastener base
through said backing sheet, embossing the por-
tion of said backing sheet in the zone of said fast-
ener base to provide a recess receiving said fas-
tener base, and clinching the prongs on the oppo-
site face of said backing sheet to attach said fas-
tener base thereon. 20

19. A method of making folders with attached
fastener bases, consisting in feeding a fastener
base having attaching prongs and binder prong
25 attaching means thereon to a backing sheet to
project the attaching prongs on the fastener base
through said backing sheet, and substantially si-
multaneously clinching said prongs on the oppo-
site face of said backing sheet and embossing said
30 backing sheet using said fastener base in the
embossing operation to provide a recess in said
backing sheet to receive said fastener base. 35

20. A device for attaching fastener bases to
backing sheets wherein the fastener bases are
provided with laterally extending attaching
prongs, comprising resiliently supported means
40 for supporting a backing sheet, said means having
an opening and an enlarged seat formed at the
upper end of said opening to provide an emboss-
ing portion, a clinching member cooperating
45 with said means for clinching and embossing, and
a punch for feeding a fastener base to project
the prongs through a backing sheet supported on
said means and for cooperation with said means
and clinching member to emboss said backing
50 sheet into said enlarged seat with said fastener
base engaged in the depression formed by the
embossment, and said member clinching said
prongs on the opposite side of said backing sheet
when said punch presses said sheet and fastener
55 base into full contact therewith. 55

FREDERICK M. ZENNER. 55
